UNITED STATES PATENT OFFICE

172,038

ELECTROLYTIC WATER TREATMENT UNIT

Edward F. McCarthy, Oakland, N. J., assignor to
Electromatic Water Treatment, Inc., New York,
N. Y., a corporation of New York

Application August 20, 1952, Serial No. 21,130

Term of patent 14 years

(Cl. D16—2)

To all whom it may concern:

Be it known that I, Edward F. McCarthy, a citizen of the United States of America, residing in Oakland, county of Bergen, and State of New Jersey, have invented a new, original, and ornamental Design for an Electrolytic Water Treatment Unit, of which the following is a specification, reference being had to the accompanying drawing, forming part thereof.

In the drawing:

Fig. 1 is a perspective view of an electrolytic water treatment unit embodying the design;

Fig. 2 is a side elevation;

Fig. 3 is an end view; and
Fig. 4 is a top plan view.

I claim:

The ornamental design for an electrolytic water treatment unit, substantially as shown.
